UNITED STATES PATENT OFFICE

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

RADIO RELAY SYSTEM

Application filed January 28, 1926. Serial No. 84,341.

My invention relates to the art of radio transmission and reception and it has particular reference to what are known as relay systems in which signals received from distant points are used to control the operation of a local transmitting station.

Numerous systems of this type have been proposed heretofore, all of which, in so far as I am aware, involve the reduction of the incoming signal to an audio frequency, which, in turn, is used to modulate the output of an oscillation generator of the radiation circuit.

Such systems have numerous disadvantages. If a single superpower station is employed to control a plurality of relay stations, it has been found necessary, in order to avoid interference between the various stations, to so arrange each separate station that it will radiate on a wave length which differs widely from that of the next nearest station. This naturally handicaps the company operating the chain of relay stations as the number of available wave lengths is necessarily limited. At the same time, such a system necessitates constant engineering attention in order that the radiated wave length may be held within the required limits of variation. Again, in the usual type of relay system, the receiving antenna tends to pick up a portion of the energy radiated from the local transmitter, resulting in unsatisfactory reception from the distant station.

Interference from static and from other stations operating on wave lengths close to those of the master station also cause numerous difficulties, with the result that no satisfactory type of relay system other than mine has, as yet, gone into extensive use.

One of the objects of my invention, accordingly, is to provide a relay system which will not be subject to the disadvantages mentioned above and which will, at all times, be substantially automatic in operation, requiring minimum supervision.

Another object is to devise a system which will clearly reradiate with freedom from power interference, static interference or interference picked-up from other broadcasting stations.

Another object of my invention is to pro-

vide a system in which the local receiving station and antenna may be, if desired, widely separated geographically from the local transmitting station, communication therebetween being maintained by means of 55 land lines, over which the signals controlling the transmitter are sent.

A further object of my invention is to provide a receiving system which will be stable in operation, which will automatically 60 compensate for losses occurring in the antenna, and which will insure the reradiation of a wave of practically constant frequency.

A still further object of my invention is to reradiate the programs or other signals 65 on the same wave length as that used by the master station, thus preventing interference between the various relay stations.

My invention, briefly stated, may be best characterized as a novel application of a 70 radio-frequency amplifier. The incoming signals are picked up on a highly directive antenna system, first amplified in a receiver, which may be regenerative, and may employ the zero beat principle of reception, then 75 further amplified in an amplifier which is carefully adjusted to prevent local oscillations, and transferred from this amplifier to wires leading to the local transmitting station. At the local station, the signals are 80 still further amplified in amplifiers using tubes of progressively increasing power, and finally reradiated into space at the frequency at which they are received.

The radiating structure is also made highly directional, the line of maximum transmission being approximately parallel to the line of best reception of the receiving antenna system, which, together with a rotatable loop at the receiving station, is used 90 to balance out signals from the local transmitting station, and prevents, to a large degree, the local receiver from picking up such signals.

The receiving amplifier may be controlled 95 as to frequency by a piezo-electric crystal oscillator, which, also compensates for antennæ losses. Undesired signals are prevented from affecting the lines between the receiving and transmitting stations by keep- 100

ing both of these lines at the same potential with reference to ground, while interference between the various units at the transmitting station is prevented by a novel use of what might be termed a balanced or push-pull amplifier so arranged that the connections leading thereto are affected by disturbances in such manner that they will cancel.

10 Referring now to the drawings, from which with the following description, a more complete understanding of my invention may be had:

15 Fig. 1 is a diagrammatic view of a preferred form of my complete relay system.

Fig. 2 is a diagram of the relative geographic arrangement of the transmitting and receiving antenna systems and illustrating the directional characteristics of each.

20 Fig. 3 shows in detail the type of receiving antenna employed in my relay system.

Fig. 4 shows the connections for the high frequency amplifier situated at the receiving station.

25 Fig. 5 illustrates diagrammatically the amplifier at the transmitting station and shows in detail the balancing arrangement referred to above.

Fig. 6 illustrates a modification of the arrangement in which the balancing loop may be connected to the transmission line between receiving antenna system and receiving amplifier.

30 Fig. 7 shows a crystal-controlled oscillation generator which I employ; and

Fig. 8 illustrates a modified system in which the first tube shown in Fig. 4 may be controlled by the oscillation generator in Fig. 7.

35 Referring now specifically to Fig. 1, the preferred form of my complete relay system is therein shown diagrammatically. The antenna counterpoise system 1, 2 is conductively connected to an inductance 3 which, in turn, is coupled to another inductance 4.

40 The inductance 4 is connected by leads 5 to an inductance 6, which is coupled to another inductance 7, both of the latter inductances being a part of the receiving station amplifier indicated by rectangle 9. A balancing loop

45 10 is rotatable on a vertical axis. This loop is adapted to be tuned by a condenser 11. Shunted across this tuning condenser is an inductance 12 which is coupled to another inductance 13 which is connected across the

50 10 leads 5 to the receiving station amplifier previously described.

An inductance 14 in the output circuit of this amplifier 9 is coupled to an inductance 55 15 from which lead the land lines 16. These

land lines are shown as broken, indicating that the transmitting station may be geographically situated some distance away from the receiving station. The land lines 16 are connected to an inductance 18 which forms

60 65 the input circuit of an amplifier indicated

by rectangle 19 located at the transmitting station.

An inductance 20 in the output circuit of the amplifier 19 is coupled by means of condensers 21 and 22 to an inductance 23 which 70 forms the input circuit of a balanced power amplifier indicated by rectangle 24. Coupled to amplifier 24 by means of lead 25 and condenser 26, is a power amplifier, indicated by rectangle 27. This power amplifier, which 75 may comprise a plurality of high-power, water-cooled tubes, feeds a tank circuit comprising a condenser 28 and inductance 29. This tank circuit is coupled through a condenser 30 to the radiating system 31. 80

Fig. 2 shows a preferred arrangement of receiving and transmitting antennæ with reference to the source of signals. The receiving antennæ 1 are spaced along a line A—B normal to the direction from which the signals 85 are to be received, the direction of best reception of the receiving antennæ being shown by a polar diagram 32. The balancing loop 10 referred to above, together with its polar diagram 33, are also shown. A receiving station 34 is situated one or more wave lengths from line A—B, along a line CD drawn between the source 35 of signals and the line A—B. The transmitting antennæ 31 are also arranged along the line A—B, while the direction of 90 maximum transmission is indicated by polar diagram 36.

In Fig. 3 is shown a detailed view of the antenna system and balancing loop indicated diagrammatically in Fig. 1. A plurality of 100 vertical antennæ 1, 1, 1, 1 as well as a corresponding number of vertical counterpoise elements 2, 2, 2, 2 are shown as supported on poles spaced along a line A—B normal to the direction from which desired signals arrive. Each antenna-counterpoise unit is separated a distance equal to one-third of a wave length from the next antenna-counterpoise unit and the total distance between the extreme elements is made equal to one wave length. 105

The lower ends of the first pair of antennæ, 1, 1 are connected together by means of bridle wires 37 and the upper ends of the corresponding pair of counterpoise elements 2, 2 are connected in the same manner 110 by bridle wires 38. The other pair of antennæ and counterpoise elements are also connected by bridle wires 39 and 40 in the same manner, and further connections 41, 42, 43 and 44 are provided whereby all of the antennæ elements 1 are in parallel and all of the counterpoise elements 2 are in parallel with reference to inductance 3.

The specific details and relative arrangement of this antennæ system are disclosed 115 and claimed in a patent to F. Conrad No. 1,689,863 of October 30, 1928, and assigned to the Westinghouse Electric & Manufacturing Company.

Inductance 3 is coupled to inductance 4 120

which is connected by conductors 5 to the receiving station amplifier, as indicated in Fig. 1. The loop 10 is tuned by condenser 11 and is rotatable around a vertical axis. Shunted across the tuning condenser 11 for the loop is an inductance 12 which is variably coupled to a second inductance 13 connected across the wires 5 leading to the receiving station amplifier 9. The operation and purpose of this loop will be explained later.

Fig. 4 is a diagrammatic view of the circuits and apparatus involved in the receiving station amplifier 9. The first tube 50 of this amplifier has shunted across its input circuit 52, 53 a crystal 54 tuned to the frequency of the signals being received. A feed back, or tickler coil 55 is variably coupled to inductance 7, and is provided with a tap 56 at or near its mid-point leading to a point 57 on the tuned input circuit 58, 59 of the second tube 60 of the series. This tube 60 is provided with a tuned output circuit comprising inductance 62 and condenser 63 and is arranged according to the disclosure contained in Rice Patent No. 1,334,118 so that it will not oscillate spontaneously. This freedom from oscillation is secured by means of the feed-back condenser 64. The output circuit 62, 63 of the second tube 60 is coupled through lead 65 and condenser 66 to the input circuit of the third tube 70, which tube 70 is also shown as neutralized by condenser 71.

The output circuit 72, 73 of this third tube 70 is coupled to the input circuit of a fourth tube 76, through lead 74 and condenser 75. The circuits accompanying tube 76 are substantially the same as those of tubes 60 and 70, comprising a neutralizing condenser 77 as well, and for that reason are not described more specifically. The output of the last tube 76 of this station amplifier is shown as an inductance 14 tuned by condenser 78, and coupled to another inductance 15 shunted across the land lines 16 leading to the transmitting station amplifier which is shown diagrammatically in Fig. 5.

Referring now specifically to Fig. 5, it will be noted that the land lines 16 are tapped into an inductance 18 in the input circuit of the first tube 82, at points 83, the potentials of which may be predetermined with reference to ground connection 84. The purpose of this type of connection will be more fully explained later.

The tuned output circuit 85, 86 of tube 82 is coupled to the input of tube 87 by means of condenser 88, both of these tubes being neutralized according to the teachings of the Rice Patent referred to previously by means of condensers 89 and 90. The output circuit 91, 92 of the second tube 87 is coupled through condenser 93 to the input circuit of the third tube 94 which latter tube has in its output another tuned circuit 95, 20, and is neutralized by condenser 96.

All of the tuned circuits referred to thus far are adjusted to be resonant to the frequency being received from the master broadcasting station, and function as radio frequency amplifiers.

The output circuit 95, 20 of tube 94 is coupled by means of condensers 21 and 22 to inductances 97 and 98 which form the input circuit of a push-pull power amplifier comprising tubes 99 and 100. Connected between the grid of tube 99 to a point on the plate circuit of tube 100 is a neutralizing condenser 101, while between the grid circuit of tube 100 and the plate circuit of tube 99 is a second neutralizing condenser 102. The purpose of these condensers is to prevent the push-pull amplifier from oscillating at undesired frequencies.

An inductance 103 shunted by condenser 104 forms the output circuit of both of these tubes, and is provided with a central tap 105 for the plate supply. Coupled to the output circuit 103, 104, by means of condenser 26 is another amplifier tube 107, preferably of the water-cooled high power type. The grid potential of the tube 107 is maintained at the best operating point by means of "C" battery 108 and inductive grid leak 109 connected across between the grid 118 and filament 111.

The output circuit of the high power tube 107 comprises a low-loss inductance 29 shunted by a tuning condenser 28, as shown in Fig. 1 and is preferably tuned sharply to the broadcasting frequency. This inductance 29 is coupled to the radiating system 31 by means of the condenser 30.

In Fig. 6 is shown a modified system of connecting the loop 10 to the lines 5 between the receiving antennae and the local amplifier station 9. The loop is shunted by an inductance 12 equivalent to the inductance 12 of Fig. 3, and is also shunted by a tuning condenser 11 and a second inductance 120. A conductor 4 connects the coupling inductance 4 to the central portion of the first inductance 12 shunting the loop. A second conductor 5 connects the lower portion of the coupling inductance 4 to the mid-point of the inductance 120 and in series with this conductor is an inductance 121. This forms what may be termed a phantom circuit.

Tracing the path of a signal impulse arising in the coupling inductance 4, it will be seen that this impulse will pass in both directions through inductance 12 and that leads 122 and 123 are consequently in parallel with reference to such impulses. The inductance 121 will therefore be affected only by signals arising in the coupling inductance 4 while the inductance 120 will have in it only signals arising in the loop 10.

An inductance 7 connected with the receiving station amplifier 9 may be variably coupled to either inductance 120 or 121 or to both of such inductances simultaneously, thus

permitting the operator to employ either the loop or the antenna system for reception, or to combine the effects of both in any desired phase relationship.

Fig. 7 illustrates a form of crystal-controlled oscillation generator which may be employed instead of the oscillator shown in Fig. 4. This oscillation generator comprises a plurality of thermionic tubes having tuned output circuits. The input circuit of the first tube 130 comprises a choke coil 131 and a C battery 132 shunted by a crystal 133 ground to have a definite frequency. By tuning the output circuit 134, 135 of this first tube to the crystal frequency, oscillations may be set up therein, which are impressed on the grid circuit of the second tube 136 through condenser 137. The output circuit 138, 139 of this second tube 136 is tuned to a harmonic of the frequency generated by the first tube 130 and is, in turn, coupled by condenser 140 to the input circuit of still another tube 141 whose output circuit 142, 143 is tuned to a harmonic of the frequency emphasized by the second tube.

It will thus be seen that, by properly choosing the crystal shunting the first tube input, and by correctly tuning the successive output circuits, any desired frequency may be obtained in the output circuit of the last tube of the series. This last tube may be a water-cooled high-power tube or a number of such tubes in parallel, and the amplifier tubes shown in the other positions are merely indicative of the manner in which the oscillation generator is constructed.

This type of crystal-controlled oscillation generator is disclosed and claimed in copending application of Donald G. Little, Serial No. 78,115, filed Dec. 29, 1925, and assigned to the Westinghouse Electric & Manufacturing Company.

Referring specifically to Fig. 8, this view illustrates diagrammatically how the oscillation generator shown in Fig. 7 may be substituted for the simple crystal control of Fig. 4. With this arrangement, there is no necessity for employing the feed-back coil 55, as the oscillation generator, which is arranged to give an output at the incoming frequency, supplies enough energy to make up for circuit losses.

As in Fig. 4, the tube 50 has a tuned input circuit comprising an inductance 7 and condenser 17. The inductance 7 is connected by leads 144 and 145, to the oscillation generator indicated by rectangle 146. This tube 50 is provided further with a tuned output circuit 147, 148, which is connected by leads 149 and 150 to the next amplifier stage, which may be essentially as shown in Fig. 4.

Having described the specific elements embodied in my improved relay system, the operation thereof will now be described.

Referring again to Fig. 1, the path of a

signal will be traced through the complete system. An incoming signal, after having been received on the antenna system 1, 2 shown in detail in Fig. 3, is transferred to the lines 5 leading from the coupling inductance 4 to the receiving station amplifier 9. This antenna system 1—2 is so arranged and proportioned that signals coming from a direction parallel to the line of A—B the antenna poles, indicated in Fig. 3, tend to cancel out in the coupling coil 3 being out of phase in the several sections of the antenna which are tied together by the bridle wires 41, 42 and 43, 44. This characteristic is fully explained in the copending application of Conrad above referred to.

On the other hand, signals coming from a direction perpendicular to the antenna line are received in the same phase in analogous sections of the antenna and are consequently reinforced. Obviously, the receiving antennæ will pick up a small amount of signal from the local transmitting station and for this reason the loop 10, which has highly directional characteristics, is used to balance out this local signal.

After having been amplified at radio frequency, the signals are transferred to land lines 16, Figs. 4 and 5, by means of coupling inductances 14, 15, which land lines are connected to an input inductance 18 forming a part of the receiving station amplifier.

It will be noted from an inspection of Fig. 5 that the filament circuit of the first transmitting station amplifier tube 82 is grounded at 84 and that the land lines 16 are connected to the input inductance 18 of this tube in such manner that each of these lines may be maintained at the same potential with respect to ground. This result is accomplished by movable contacts 83. By means of this connection, the land lines are prevented to a large extent from radiating energy and at the same time any energy picked up by these land lines tends to cancel in the inductance 18. This manner of connection secures a very important result, i. e., the prevention of feed-back from such lines to the receiving antenna and the elimination of pick-up by these lines of the locally radiated signal.

In the transmitting station amplifier 19, 24, 27, the incoming high frequency signal is repeatedly amplified but its frequency is not changed. This amplifier, as explained in connection with the description of Fig. 5, employs tubes of successively higher powers.

In the construction of this amplifier, great difficulty was at first experienced due to feed-back between the various units thereof and consequent undesired oscillation. Such feed back is obviated in the following manner; The output inductance 20 of the first section of the transmitting station amplifier is connected by means of coupling condensers 21

and 22 to the input circuit of what may be termed a balanced power amplifier consisting of two power tubes 99 and 100, which tubes are connected with their filament circuits in parallel and their output circuits comprising portion of a single inductance 103. The inductances 97 and 98 shown as connected across the input circuits of these two power amplifier tubes are high frequency choke coils which serve as grid leaks. As explained before, this power amplifier is neutralized according to the teachings of the Rice Patent 1,334,118 to prevent parasitic oscillations.

The filament circuit of this power amplifier has a ground connection 125. The central point of the coil 20 is maintained at ground potential, as far as regards the radio-frequency currents. The leads 113 are connected to points of the coil 20 symmetrically situated as regards said central point. Consequently, the radio-frequency potential between either lead 113 and the ground is of the same amplitude for each lead. If, from any cause, an extraneous potential difference between the ground and the amplifier is present, it will affect the two leads 113 in the same way. Any disturbance picked up by these leads will be in phase in each and will cause the grids of the amplifier tubes to vary synchronously as to potential. The currents in the output inductance will accordingly be in opposite directions so there will be no tendency for an oscillating current to be set up in the circuit comprising the inductance 103 and condenser 104. This arrangement nullifies the effects of undesired energy picked up by leads 113 from either the transmitting antenna or other portions of the amplifier. On the other hand, when signals are impressed on the input circuits of this power amplifier through coupling leads 113, it is obvious that the grids will acquire charges differing in potential. The net effect of such differences will be to set up a circulating current in the circuit comprising inductance 103 and condenser 104. This output circuit is coupled to the input circuit of a power tube 107 by means of a coupling condenser. The output circuit of this tube 107 is formed by an inductance 29 and a condenser 28 constructed to have minimum losses and is commonly known as a "tank circuit." This circuit is very carefully tuned to the broadcasting frequency and is coupled through condenser 30 to the radiating system 31. This general type of coupling is disclosed and claimed in the patent to F. Conrad, No. 1,652,516 of December 13, 1927, and assigned to the Westinghouse Electric & Manufacturing Company.

Incoming signals are accordingly re-radiated from the local transmitter still at the frequency received. The various amplified stages have no function other than that of

increasing the amplitude of an extremely weak signal until it is sufficiently powerful to be re-radiated.

In order to insure that even the weakest of received signals may be re-radiated with maximum intensity, I may make use of a re-generative receiver operating on the homodyne principle.

Referring again to Fig. 4, the first tube 50 is equipped with a tuned input circuit comprising inductance 7 and condenser 17 and coupled to this inductance 7 another inductance 55 in the plate circuit of the tube. This forms a "tickler" re-generative arrangement and the coupling between these inductances may be made so close that this tube will generate oscillations. The oscillations generated by this tube are repeatedly amplified as they pass through the whole system and are eventually re-radiated from antenna 31.

In order to secure a constant frequency of radiation this first tube 50 is shown as having a piezo crystal 54 shunted across its input circuit 52, 53. This crystal serves to maintain the frequency of oscillations of this tube substantially constant so that variations in the tuning of the antenna circuit occasioned by wind, etc., will not appreciably affect the frequency being re-radiated from the transmitting station. The frequency to which the crystal 54 is ground should be the same as that of the signal it is intended to receive. This ensures that the re-radiated frequency will be the same as the frequency sent out by the master station.

The crystal shown may be, if desired, replaced by the type of oscillation generator shown in Fig. 7 and previously described. The manner in which such oscillation generator may be employed is shown in Fig. 8 and has also been described.

In the event that the signals being received from the master station, or from neighboring relay stations, are of sufficient intensity, the tickler coil 55 and crystal control 54 may be omitted from the first section of the amplifier shown in Fig. 4. With these omissions, the tendency toward self-oscillation in the amplifier is lessened, and, in many instances, the modulation of the transmitter output is improved.

Another and very important phase of my invention, which is illustrated in Fig. 2, deals with the problem of interference by the locally received signals and the locally transmitted signals. In most previous attempts at relaying, considerable difficulty has been experienced by reason of the receiving antenna picking up such a large proportion of the locally radiated energy as to seriously affect the reception. I have, by means of my invention, entirely obviated this defect. The receiving antenna as shown somewhat in detail in Fig. 3 and described and claimed in my Patent No. 1,689,863 of October 30,

1928, has very pronounced directional characteristics. As indicated by polar diagram 32 the reception in the direction of a line A—B parallel to the antenna poles is quite poor, while reception on a line normal thereto is extremely good. The transmitting antenna is shown at 31 and is so arranged that all of the separate antenna units, both of the receiving and of the transmitting antennæ, are in alignment.

19. It will be noted that the transmitting antennæ consist of four sections, each of which, in practice, is composed of a vertical antenna and counterpoise connected through an inductance. These sections are horizontally separated by distances corresponding to definite fractions of the wave length, λ , to be received, as shown in the diagram. The antenna sections 31 in line with the receiving antenna are each separated by a distance equal to one-half of the wave length being received in meters, while another antenna section 31 is separated from the line-up a distance equal to one-fourth of a wave length.

20. Situated a distance one-half wave length from the receiving antenna line-up is a loop rotatable about a vertical axis, the polar diagram of which is shown at 33. At one-half wave length from this loop is located the receiving station containing the receiving amplifier apparatus and circuits as illustrated in Fig. 4. The purpose of this spacing is to secure a better balance in the received signals from the source shown at 1, 2 and is fully explained and claimed in my co-pending application referred to above.

21. As will be seen from the polar diagrams of the receiving and transmitting antennæ, the lines of best reception and transmission are parallel or approximately so. The receiving antennæ therefore, pick up but a small amount of energy from the transmitting antennæ, which latter may be situated a number of miles away. This small amount of energy is nevertheless troublesome and the loop 10 is accordingly used to balance out such energy by introducing into the transmission line, as shown in Fig. 3, an equal amount of energy 180° out of phase therewith. This relative arrangement of receiving and transmitting antennæ together with the position of the balancing loop with respect to the direction from which signals are desired, is an important part of my invention.

22. It will thus be seen that by employing my invention in connection with broadcasting of intelligence, marked economy of operation may be attained. A single high power station is enabled to control simultaneously, a large number of relay stations and each relay station, in turn, serves to augment the power being sent out by the first station. All of the stations in the system will operate on the same wave length and it is obvious that even though there be some stations be-

yond the range of the master or control station, the energy sent out by near-by relay stations will be sufficient to operate such distant stations.

23. A minimum of trained men is required to operate each separate relay station as my system when once adjusted, is practically automatic in its operation.

24. Although I have illustrated and described herein certain specific embodiments of my invention, I am fully aware that within the bounds of such invention many other modifications are possible, and I do not desire to be limited except in so far as is necessitated by the prior art and by the spirit of the following claims.

25. I claim as my invention:

1. In combination, a source of radiant energy, means adapted to receive such energy, said means comprising a plurality of substantially vertical conductors geographically situated along a line normal to the direction from which the energy is received, a second source of radiant energy controlled by said receiving means, said second source being also located on the same line normal to the direction from which energy is received, and additional means, comprising a loop-antenna, for preventing said second source from interfering with the reception of signals by the receiving means.

2. In a radio relay-system, means for impressing received radiant energy on a vacuum tube device, means for maintaining said device in an oscillatory state at the frequency of the received energy, means for preventing the frequency of said oscillations from changing, an amplifier for increasing the amplitude of said oscillations, and a radio-transmitter controlled directly by said amplifier.

3. In combination, an amplifier having an output circuit, a second amplifier comprising a plurality of thermionic devices arranged in push-pull relation and having input and output circuits, a transmission line so disposed as to couple the output circuit of the first-mentioned amplifier to the input circuit of the second amplifier, and means for maintaining the conductors constituting said line, and the homologous parts of said last-mentioned amplifier at equal effective potentials with respect to ground.

4. In combination, an amplifier having an output circuit including an inductance, a second inductance, a plurality of vacuum-tube devices connected in push-pull relation to the second inductance, and circuit connections from the first inductance to separated points on the second inductance at equal effective potentials with respect to ground, whereby radiation from circuit connections is minimized.

5. In an amplifying system, a vacuum-tube device having a cathode, a grid and an anode, an inductance connected at one terminal to said anode and at its other terminal to the

grid, a capacity included in the last named connection, a second inductance, a plurality of vacuum-tube devices connected in push-pull relationship to said second inductance, and connections from the first inductance to separated points on the second inductance at equal effective potentials with respect to ground.

6. In a relay system, a radio signal receiver, an amplifier for the received signals, a radio transmitter situated at a distance from said signal receiver, connections between said radio transmitter and said amplifier, and means whereby said connections may be maintained at equal effective potentials with respect to ground insofar as potentials impressed thereon from said transmitter are concerned, whereby parasitic oscillations are prevented from being set up in said system by reason of feed-back from said transmitter.

7. In a radio relay system, means for receiving signals, means for amplifying the received signals, said amplifying means comprising units separated a substantial distance apart, means for re-radiating the amplified signals, circuit connections between the receiving means, the amplifying means and the radiating means, and means whereby the connections uniting space separated units of the amplifying means are restrained from radiating.

8. In combination, a directional receiving antenna system, a directional transmitting antenna system so arranged that the direction of maximum reception of the receiving antenna system is substantially parallel to the direction of maximum radiation of the transmitting antenna system, and means comprising a movable loop for minimizing the effect of the transmitting antenna system on the receiving antenna system.

9. In a radio relay system, a receiving antenna having a non-uniform directional characteristic, a transmitting antenna located in a direction from the receiving antenna in which the receiving antenna has a minimum effectiveness, a supplemental receiving antenna having an adjustable non-uniform directional characteristic and means for superposing the energy received by said supplemental antenna upon the energy delivered to the receiving antenna by the transmitting antenna in a direction to tend to counteract it, whereby adjustment of the directional characteristic of said supplemental antenna may cause said counteracting to be complete.

In testimony whereof, I have hereunto subscribed my name this 26th day of January, 1926.

FRANK CONRAD.
